UNITED STATES PATENT OFFICE.

EDWARD URDANG AND HARRY H. LE VITA, OF NEW YORK, N. Y.

PERFORATING MACHINE.

Application filed September 24, 1923. Serial No. 664,441.

To all whom it may concern:

Be it known that we, EDWARD URDANG and HARRY H. LE VITA, both citizens of the United States, residing at New York city, 5 boroughs of Manhattan and the Bronx, respectively, in the counties of New York and Bronx, respectively, and State of New York, have invented certain new and useful Improvements in Perforating Machines, of 10 which the following is a specification.

This invention relates to perforating machines of the general type in which the perforating or puncturing instrument is reciprocated rapidly by means of a power 15 device such as an electric motor, the entire device being portable or guidable by the hand of the operator while in operation.

Among the objects of the invention is to provide a relatively cheap, simple, and yet 20 effective device of the nature above indicated, the same having peculiar adaptability for durability and reliability as well as for ease and efficiency of operation.

More specifically, our improvement comprises a casing in which all of the operating 25 parts are housed except the reciprocating member and which casing is peculiarly constructed so as to assist in the manipulation and guiding of the needle or perforating 30 instrument along the pattern.

Another object of the invention is to simplify the construction of the casing mechanism not only with respect to facility 35 of formation and assemblage, but also as to the bearing connections for the movable parts within the casing.

This application constitutes a substantial continuation in some of the principal features of our previous application filed 40 the 19th day of August, 1922, Serial No. 582,838, and allowed on the 24th day of July, 1923.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is an end elevation of the device, 55 a part of the end of the casing extension

being in section to better indicate the operating mechanism.

Fig. 2 is a side elevation of the device with parts in section.

Fig. 3 is a horizontal section on the line 3—3 of Fig. 2.

Fig. 4 is a detail perspective of a side part of the casing.

Figs. 5 and 6 are detail end and side views of a modified form of cam.

Referring now more specifically to the drawings we show a casing comprising a main body portion 10, constituting a hand hold or grip, and from which extends laterally a wing portion 11. The body 70 casing includes a base or bottom 12 adapted to glide over the pattern or work, and including also front and rear sides 13 and 14 respectively, either integral or separate from each other. The top of the casing is 75 indicated at 16. The several parts of the casing may be secured detachably or otherwise by any suitable means such as screws 18. The side wall members include flat portions 19 formed at right angles to wing 80 extensions 20, and between the extensions 20 is located an end wall 15 parallel to the panels 19. The bottom of the wing 11 is a plate 17 which is provided with a vertical angular extension 21 with which end portions 85 of the panels 19 co-operate making a complete closure for the mechanism within the casing.

Fixed in any suitable manner upon the base 12 is a motor comprising a frame 23 from which leads a shaft 25 from the rotor 26 of the motor. The shaft extends into the wing extension 11 of the casing and fixed removably to the end of the shaft is an actuator shown in Figs. 1 and 2 as comprising 95 a double throw cam 22. On the side of the cam remote from the shaft and in alignment with the shaft is formed a pit 24 in which is fitted an anti-friction bearing ball 27 extending into a pit 24' formed in the wall 15. 100 The cam 22 is provided preferably with a peripheral groove 22' for co-operation with a second bearing ball 28.

The feed wires 29 for the motor are connected to binding posts 30 and 31, and associated with the binding post 30 is a contact 32 which extends laterally toward but spaced slightly from the panel 19 of the front wall 13. A finger piece in the nature of a push button 33 projects through a hole 110

in this portion of the casing in convenient position to be pushed by the operator's thumb as he grasps and manipulates the device and said push button is carried by a 5 contact spring 34 leading toward the rotor, the circuit being closed by pressing inward upon the button until the contacts 32 and 34 are brought together.

37 indicates a vertically mounted reciprocating bar guided for vertical movements in 10 a sleeve 38 preferably screw threaded into the bottom wall 17 of the casing extension. The bar has a head 39 on its upper end within the casing. The bearing ball 28 rests 15 within a pit formed in the upper surface of the head and constitutes a contact member between the cam and the bar, and a spring 40 surrounding the bar between the head and the sleeve serves to keep the bar elevated and with bearing ball in contact with both the head and the cam. The spring of course permits the throw of the cam to project the bar downward. A needle or punch 41 of any suitable design, according to the 20 work to be performed, is carried preferably detachably by means of a chuck 42 at the lower end of the bar.

As shown in Figs. 1 and 2 the bar will be reciprocated downward twice for each rotation of the motor shaft 25. In Figs. 5 and 6, 30 however, we show a cam 22^a having a single throw so that but one reciprocation of the bar will be effected at each rotation of the shaft. Otherwise the parts are constructed 35 and operate similarly to the form in Figs. 1 and 2. The cams are attached separably to the shaft for interchange or adjustment as by means of a set screw 43 operating through a hub 45 formed on the cam.

40 In the use of the device the operator grasps the main portion of the casing, with his thumb applied close to the button 33. With the device thus grasped or held the operator may move the entire device freely 45 over the table or work anywhere within the limits prescribed by the wires 29, and when the button 33 is pressed the motor will rotate rapidly, causing rapid reciprocations of the bar 37 and needle 41. The bearing sleeve 38 being of considerable length gives a 50 steady position for the bar limiting it only to reciprocations. The device is very small and compact and may be guided reliably along any desired course or pattern to be 55 perforated or otherwise treated. Usually in work of this kind the pattern is laid upon a number of plies of paper so that a number of sheets may be perforated at the same time.

60 To facilitate the guiding of the machine over a pattern along regularly formed lines, as for instance straight lines, the body of the casing includes flat faces or panels 44 both lying in planes substantially tangent to a 65 small imaginary circle whose center is the

axis of the needle 41. A straight edge therefore laid close to a straight line to be perforated may be employed to guide the machine by contact with either of the surfaces 44 as suggested by the dot and dash lines 46. The operator by holding the straight edge in one hand may move the machine in his other hand to cause the needle to move along a straight line as will be readily understood. 70

We claim:

1. In a perforating machine, the combination of a motor, a reciprocating tool bar remote from the motor, an actuating member extending between the motor and the bar for reciprocating the latter from the motor, 80 a casing inclosing the motor and also said actuating member and in which the end of the actuating member remote from the motor is operatively supported, said motor casing serving as a hand grasp and as a 85 supporting means for the device in operation, and means formed on the sides of the motor casing serving as guiding means in connection with a straight edge arranged substantially in alignment with the side of 90 the reciprocating tool bar, substantially as set forth.

2. In mechanism of the nature set forth, the combination of a reciprocating bar, a 95 needle attached to one end thereof, power means to reciprocate the bar, and means to carry and control the action of the power means, said means comprising a casing movable over the work and having a straight portion lying in a plane substantially tangent to the side of the bar and including also a finger piece to be operated coincident with the manual operation of the casing, substantially as set forth.

3. The herein described perforating machine comprising a casing manually movable over the work, a rotary device including a shaft within the casing, means to control the rotation of the shaft coincident with the manual manipulation of the casing, an anti-friction bearing support for the otherwise free end of the shaft co-operating with the end wall of the casing, a cam connected to the shaft adjacent to the anti-friction device, a bar mounted in the casing and acted upon by said cam for reciprocating it perpendicularly with respect to the shaft, and a tool carried by the bar for operating upon the work over which the casing is movable. 110

4. In a perforating machine, the combination of a casing having a lateral extension, a guide sleeve secured to the extension, a reciprocating bar fitted slidably in the sleeve, a rotary motor shaft journaled in the casing perpendicular to the bar, and means between the shaft and the bar for imparting reciprocations to the bar from the rotation of the shaft, said means comprising a cam affixed to the end of the shaft 125 130

- and having a peripheral groove eccentric to the axis of the shaft, a contact member between the cam groove and the end of the bar, whereby the rotation of the shaft and 5 cam causes movement of the bar in one direction, and means acting to reciprocate the bar in the opposite direction, maintaining said contact member in said groove.
5. In a perforating machine, the combination of a main casing having a lateral extension including an end wall with a pit formed on the inner surface, a power shaft mounted in the casing and extending horizontally into the extension in alignment 10 with said pit, a cam fixed to the end of the power shaft adjacent to the pit and having an eccentric periphery, the wall of the cam member adjacent to the pit being provided 15

also with a pit, a centering member located in said pits and serving to support the end 20 of the shaft having the cam, a bar mounted to reciprocate in the casing extension at an angle to the power shaft and having a head adjacent to the cam, a spring surrounding the bar and tending to hold the head in 25 close proximity to the cam member, and a contact member acting between the cam and said head and through which and the rotation of the shaft and the eccentricity of the cam the bar is forced away from the axis 30 of the shaft and against the tension of the spring.

In testimony whereof we affix our signatures.

EDWARD URDANG.
HARRY H. LE VITA.
